ARTHUR G. HOLLAND, OF BRIDGEPORT, CONNECTICUT, ASSIGNOR TO SIDNEY BLUMEN-
THAL & CO. INC., OF NEW YORK, N. Y., A CORPORATION OF NEW YORK

FLOOR COVERING OR RUG

Application filed August 29, 1931. Serial No. 560,069.

This invention relates to an improvement in floor coverings or rugs, and particularly to such coverings or rugs as include a fabric or textile surface permanently combined with a resilient backing material.

An object of the invention is to provide such a structure in which a sheet of pile fabric is secured to a sheet of sponge rubber, so that the latter will serve as a resilient backing for the former while at the same time acting to prevent slipping or creeping of the rug.

Another object consists in providing a rug or floor covering having a finished edge 15 formed by turning under a marginal portion of the fabric.

A further object consists in providing a rug or floor covering having an edge portion of the character indicated in which the peripheral bottom surface is the same as the top surface.

Another object consists in providing such a structure in which the body of the rug is formed of a pile fabric secured to a sheet 25 of sponge rubber, while the edges are formed of two thicknesses of the pile fabric secured together back to back.

A further object consists in providing such a structure in which the resiliency of the peripheral portions is substantially the same as that of the body portion.

Another object is to provide certain improvements in the form, construction and arrangement of the several parts whereby 35 the above named and other objects may effectively be attained.

A practical embodiment of the invention is shown in the accompanying drawings, in which

40 Fig. 1 represents a top plan view on an enlarged scale of a corner of rug or floor covering, the remainder being broken away;

Fig. 2 represents a bottom plan view of the same, a portion of the sponge rubber backing 45 being broken away, and

Fig. 3 represents a vertical section along the line III—III of Fig. 1.

As shown in the drawings, there is provided a pile fabric 1 of usual construction, 50 including warp threads 2, weft threads 3, and

loops of pile 4. Intimately and firmly secured to the back of this fabric is an impervious layer of flexible backing material 5, such as rubber. This layer may be of any desired thickness but should desirably be only thick 55 enough to ensure its remaining impervious in use and to reinforce the fabric adequately, while permitting the greatest possible flexibility. A relatively thick layer of sponge rubber 6 is secured to the bottom of the layer 5, by any suitable means such as cement or vulcanizing, and it may be desirable to have this sponge rubber of a high degree of porosity and resiliency so as to provide, in effect, an air cushion beneath the flexible but 60 relatively non-resilient upper rubber portion. This effect is enhanced by leaving the lower surface 7 of the sponge rubber in its natural porous open state. In this state also the surface is of such roughness as to hold firmly 65 upon the floor, however smooth, thereby completely preventing slipping or creeping of the floor covering or rug.

A feature of this invention is the formation of a finished edge, as shown, in which the 75 sponge rubber base 6 is made to terminate at a point 8 spaced somewhat from the desired extreme outside edge of the rug. The projecting marginal portions of fabric backed by the layer of rubber 5 are turned under 80 and inward, and the contacting backing portions are joined together into a double layer backing 9 having fabric above, beneath, and beside it. As shown in Fig. 3 the inturned edge of the fabric abuts the edge of the base 6 at the point 8 and may desirably be secured thereto.

With this construction it results that a pile floor covering is provided having a softness 90 and resiliency out of all proportion to that normally expected in a pile of the length shown. At the same time a very neatly finished edge is formed, while the sponge rubber base is well concealed when the rug is in use. 95 By the expedient of using the pile fabric double at the edges its normal softness and resiliency is doubled, so as to approximate that of the body of the rug, hence it becomes difficult or impossible to notice the existence 100

of this peripheral construction when stepping or walking upon the rug.

It is evident that various changes may be resorted to in the form, construction, material and arrangement of the several parts without departing from the spirit and scope of my invention, and hence I do not intend to be limited to the details herein shown and described, except as the same may be set forth in the claims.

What I claim is:

1. A floor covering or rug of the character described comprising, a pile fabric surface portion, a flexible intermediate backing portion and a resilient base portion, the peripheral portions of said pile fabric and backing being folded under so as to form an edge having pile fabric on the bottom of the rug as well as on the top.
2. A floor covering or rug of the character described comprising, a pile fabric surface portion, a flexible intermediate backing portion and a resilient base portion, said base portion terminating at a point spaced from the outer edge of the rug, and the peripheral portions of said pile fabric and backing being folded under so as to form an edge consisting of two layers of fabric and backing in back to back relationship.
3. A floor covering or rug of the character described comprising, a pile fabric surface portion, a flexible intermediate backing portion and a resilient base portion, said base portion terminating at a point spaced from the outer edge of the rug, and the peripheral portions of said pile fabric and backing being folded under and secured at their in-turned edge to the outer edge of the base portion, so as to form an edge for the rug consisting of two layers of fabric and backing in back to back relationship.
4. A floor covering or rug of the character described comprising, a pile fabric surface portion, a flexible intermediate backing portion and a resilient base portion, portions of the rug being formed of two layers of fabric and backing in back to back relationship, and the resiliency of said last named portions being approximately the same as that of the remainder of the rug.
5. A floor covering or rug of the character described comprising, a pile fabric surface portion, a flexible intermediate backing portion and a resilient base portion, peripheral portions of the rug being formed of two layers of fabric and backing in back to back relationship, and the resiliency of said peripheral portions being approximately the same as that of the main body of the rug.
6. In testimony, that I claim the foregoing as my invention, I have signed my name this 26th day of August, 1931.

ARTHUR G. HOLLAND.
